UNITED STATES PATENT OFFICE.

JOHANNES PFLEGER AND FRIEDRICH OTT, OF FRANKFORT-ON-THE-MAIN, GERMANY,
ASSIGNORS TO ROESSLER AND HASSLACHER CHEMICAL COMPANY, OF NEW YORK,
N. Y., A CORPORATION OF NEW YORK.

ELECTROLYTIC APPARATUS.

1,186,937.

Specification of Letters Patent. Patented June 13, 1916.

Application filed October 2, 1913. Serial No. 792,973.

To all whom it may concern:

Be it known that we, JOHANNES PFLEGER and FRIEDRICH OTT, subjects of the Emperor of Germany, and both residents of Frankfort-on-the-Main, Germany, have invented 5 certain new and useful Improvements in Electrolytic Apparatus, of which the following is a specification.

This invention relates to an improvement 10 in electrolytic apparatus for the production of alkali metal, such as metallic sodium, from molten alkali haloids, such as sodium chlorid, and it refers particularly to the protection of an essential part of the apparatus 15 against the harmful action of products generated in the process, such as chlorin gas for instance.

In a copending application filed June 16, 1913, Serial No. 774,039, we have shown how 20 to make the well known apparatus of Castner a universal apparatus for the electrolytic production of alkali metal and to use said apparatus especially for the utilization of alkali-haloids, by protecting the 25 outer surface of the collector of the generated alkali metal by a material resistant to the action of the products generated at the anode.

We have found that one may use advan- 30 tageously for the protection of the collector a solidified or homogenous layer of salt, such as sodium chlorid, or a mixture of salts, such as sodium chlorid and potassium chlorid, resistant to the products generated 35 by the electrolysis.

In order to constantly maintain the protecting layer it is advisable in some cases to continuously or from time to time conduct off some heat from the metal collector. This 40 is simply effected by partly constructing the collector as a hollow cylinder, through which a cold gas or liquid current of an adequate strength can be passed.

For the better understanding of our in- 45 vention reference is made to the accompanying drawing, which represents a sectional elevation of a convenient form of apparatus for carrying our invention into effect.

The apparatus comprises a receptacle A, 50 of iron or any suitable material, which serves as a container for the electrolyte as well as for the electrodes with the other appurtenances necessary thereto. The cathode 1, of iron or any other suitable material,

is entered preferably from below through 55 the bottom of A and extends upward into the vessel from which it is suitably insulated. The anode 2, preferably made of carbon, is suspended at the top of the vessel, insulated from same by suitable material, 60 and passes downward until the working surface at its lower end is opposite to that of cathode 1. The electrodes 1 and 2 are separated by a wire screen 3 which is connected with an iron receptacle 4, the upper 65 end of which is closed by a lid.

The electrolyte reaches somewhat below the rim of vessel A and leaves ample space between anode and receptacle 4 into which the chlorin gas escapes. The outside of 70 the receptacle 4, which is exposed to said chlorin gas, is covered with a layer 5, formed of a salt or mixture of salts, thus protecting receptacle 4 against the chlorin. Inside receptacle 4 the level of the electro- 75 lyte is somewhat higher than outside, owing to the low specific gravity of the metal 6 as obtained by the process. The chlorin gas generated escapes through pipe 7. The metal obtained by the electrolysis may be 80 removed in any of the well known ways, either by dipping same out or by providing a contrivance for the drainage of said metal.

The salt or mixture of salts is applied 85 as a protective coat to the outside of the collector by dipping the same, closed below by a detachable bottom, into the fused salt and removing it again quickly from the same, there may also be added to the salt 90 such materials which with the prevailing working conditions are indifferent to the electrolytic products. It is not necessary that the insulating layer be perfectly solidified, as viscid homogeneous coats may also 95 provide sufficient protection. The change of physical state consisting in the transformation of the salt layer from the solid to the viscid state or vice versa as well as the maintenance of the viscid state is effected in 100 the simplest way by conducting off the required quantities of heat from the collector. The loss caused by the quantities of heat thus conducted off in order to accomplish this purpose is practically of no importance. 105 Conducting off the heat offers also the further advantages that the separated alkali metal is cooled off somewhat, which is de-

sirable in any case, whether one dips out the alkali metal or whether one drains same off.

Where we use the general expression 5 "salt" in the claims, we mean to include both a mixture of salts as well as a single salt, and when we use the term "solidified" in the claims we mean to include the salt in such physical state that it will form a 10 protective coating on the outer wall of the collector of the generated alkali metal, whether the salt is actually solid or not.

We claim:

1. In an apparatus for the electrolysis of 15 fused alkali salts, the combination with positive and negative electrodes having their working faces in close juxtaposition to each other, of a gauze or screen interposed between said electrodes, a superposed vessel or dome for receiving the separated metal and 20 a halogen-resisting coating on the outer surface of said receiving vessel comprising solidified salt.
2. In an apparatus for the electrolysis of 25 fused alkali salts, the combination with positive and negative electrodes having their

working faces in close juxtaposition to each other, of a gauze or screen interposed between said electrodes, a superposed vessel or dome for receiving the separated metal and 30 a chlorin-resisting coating on the outer surface of said receiving vessel comprising solidified salt.

3. In an apparatus for the electrolysis of fused alkali salts, the combination with 35 positive and negative electrodes having their working faces in close juxtaposition to each other, of a gauze or screen interposed between said electrodes, a superposed vessel or dome for receiving the separated metal and 40 a chlorin-resisting coating on the outer surface of said receiving vessel comprising solidified sodium chlorid.

In testimony whereof we have signed our names to this specification in the presence 45 of two subscribing witnesses.

JOHANNES PFLEGER.
FRIEDRICH OTT.
